UNITED STATES PATENT OFFICE.

HENRY BURGESS, OF AKRON, OHIO.

RAIL-DRILL.

SPECIFICATION forming part of Letters Patent No. 243,033, dated June 14, 1881.
Application filed January 31, 1881. (No model.)

To all whom it may concern:

Be it known that I, HENRY BURGESS, of Akron, in the county of Summit and State of Ohio, have invented a new and useful Improvement in Rail-Drills, of which the following is a specification.

This invention relates to that class of drills used for piercing the web of railroad-bars near the ends thereof with holes to receive the bolts used in forming the fish-joint.

Heretofore ratchet-drills have generally been employed for this purpose, although in some instances the drill is actuated by a hand-crank through the medium of bevel-gears. The objection to these drills is that but the power of one man can be applied to drive the drill, unless the machine be made very cumbrous and heavy, and the ratchet-drills are driven at a low speed at a great expense of time.

The object of this invention is to afford a simple, light, cheap drill adapted to employ the strength of two men and to rapidly accomplish the desired work.

To that end it consists of a combination, with a clamp to hold the rail, of a drill-stock driven by two hand-cranks through the medium of bevel-gears and a feeding device.

The invention is illustrated by the accompanying drawings, wherein Figs. 1 and 2 represent a front and side elevation, respectively, of my improved rail-drill.

The frame consists of two parts, the part A being simply a bar bent at right angles at its upper end and terminating at the lower in a fork, B B, the ends whereof are turned back to grasp the farther edge of the rail-base, thereby holding it against the drill and preventing lateral motion. The other part of the frame consists of the pieces C, C', and G, all firmly

bolted together, the upper part of the piece C being turned round to fit and slide in a corresponding hole in the piece A, while the piece G slides in a slot in the part A.

D is the drill-shaft, journaled in the pieces C and A, and terminating in the drill-stock D', and connected at its upper end with the feed-screw I.

A bevel-gear, E, attached to the shaft D, meshes with side gears, F F, which latter are mounted upon short shafts journaled in the pieces C and G, respectively, and terminating in squared shanks for the reception of cranks, by which they are turned, the cranks not being shown, as their arrangement and operation are obvious.

K is a loose jaw sliding in the slot in the part A, fastened by the nut J, and adapted to grasp the edge of the rail-base opposite the hooks B B.

I claim as my invention—

In a rail-drill, the combination, with a bar or frame having at one end hooks to grasp the flange of the rail and at the other a feeding-screw, of a frame for bearing the drill and actuating mechanism, the frame consisting of the bars C, C', and G jointly with hooked bar A, and adapted by means of the feeding-screw to move along said bar or frame A in the line of the drill, substantially as shown, and for the purpose specified.

In testimony that I claim the foregoing I have hereunto set my hand this 20th day of January, 1881.

HENRY BURGESS.
